US00D662603S

(12) **United States Design Patent**
Greenizen

(10) **Patent No.:** **US D662,603 S**
(45) **Date of Patent:** **** Jun. 26, 2012**

(54) **MAGNETIC RACK**

(75) Inventor: **Kurt E. Greenizen**, Bradford, MA (US)

(73) Assignee: **EMD Millipore Corporation**, Billerica, MA (US)

(**) Term: **14 Years**

(21) Appl. No.: **29/358,973**

(22) Filed: **Apr. 2, 2010**

(51) **LOC (9) Cl.** **24-02**

(52) **U.S. Cl.** **D24/227**

CLAIM

The ornamental design for magnetic rack, as shown and described.

DESCRIPTION

FIG. 1 is a top view of the rack;

FIG. 2 is a bottom view of the rack;

FIG. 3 is a front view of the rack;

FIG. 4 is a perspective view of the rack;

FIG. 5 is a side view of the rack (the opposite side view is a mirror image); and,

FIG. 6 is a rear view of the rack.

The portions of the magnetic rack shown in broken lines form no part of the claimed design.
